UNITED STATES PATENT OFFICE

AUSTIN H. HART, OF GREENWICH, CONNECTICUT, ASSIGNOR, BY MESNE ASSIGNMENTS, TO REVERE COPPER AND BRASS INCORPORATED, OF BALTIMORE, MARYLAND, A CORPORATION OF MARYLAND

RADIATOR FOR HIGH-PRESSURE SYSTEMS

Application filed July 21, 1927. Serial No. 207,529.

This application is a continuation-in-part of my United States application, Serial Number 147,353, filed November 18, 1926, which has matured into Patent No. 1,641,586, granted Sept. 6, 1927.

As is well known in this art, radiators built up of flat tubular sections have heretofore not been adapted for use in systems having pressure over fifty pounds; for pressures over fifty pounds it has always been necessary to use cylindrical tubing arranged in gridiron fashion.

The main object of the present invention is to provide a heating system in which the radiator units are each built up of flat tubular sections provided with heat radiating fins which reinforce the flat tubular sections and adapt them for use without distortion in systems operating at very high temperature and under pressures greater than the flat radiator sections of the prior art have ever been able to withstand.

In the using of these finned radiator sections, it has been found necessary to devise special couplings to secure the sections of a radiator unit to each other in order to provide for the ready assembly of the fins upon the sections, and of the sections to form a radiator unit. These couplings and the finned flat tubular sections therefore constitute separate inventions, which, however, are dependent upon each other as parts of the system.

Another object of this invention is to provide heating systems of this type with couplings having separate parts capable of being drop forged, and otherwise cheaply manufactured and assembled.

A further object of the invention is to provide systems of this type with couplings which enable the heating fluid to be conducted into and out of the radiator units at any of the coupling joints connecting adjacent sections to each other.

Other objects of the invention will become apparent as the detailed description thereof proceeds.

In the drawing:—

Figure 1 is a fragmentary side elevation of a radiator heating unit forming part of

this system, with parts of the radiator sections of the unit and the couplings broken away to illustrate the method of assembling the sections;

Figure 2 is a fragmentary enlarged sectional elevation of the couplings shown in section in Figure 1;

Figure 3 is an end elevation of one of the coupled ends of the radiator unit with a closure cap removed to show a coupling in end elevation; and

Figure 4 is a plan view of the radiator unit.

As shown in the drawings, the radiator unit, designated as a whole by the reference character R, comprises a plurality of sections 1, each of which includes a pair of sheet metal plates 2 and 3 preferably of brass or copper, welded together at their respective edges 4 and 5 and shaped to form a flat tube closed at each end, and having flat substantially parallel sides 6 and 7.

The opposite ends of each section 1 are inset from the sides 6 and 7 to form header faces 8 and 9 substantially parallel to the faces 6 and 7. The faces 8 and 9 are provided with aligned apertures 10 and 11 respectively, through which project the screwthreaded bosses 12 and 13 of the coupling members 14 and 15 respectively, each of which is provided with a bridge plate 16 extending diametrically across the coupling member. The center of each plate 16 is apertured to receive the shank of a rod 17 which is headed at each end to engage the plates 16 and to limit the degree of separation of the members 14 and 15.

A cap 18 may be used to close either of the coupling members 14 and 15 at the ends of a built up radiator unit, and coupling nuts 19 are used to connect the coupling members 14 and 15 of adjacent sections in the unit.

The heating fluid may, of course, enter the radiator unit at either end of the coupled headers of the unit, but as this particular type of heating apparatus is frequently used with its sections horizontally arranged, I provide a special T-coupling 20, having a branch pipe 21 extending therefrom, to be substituted for

any of the ordinary couplings 19 which connect the sections to each other.

The plates of each section are preferably made of brass or copper, and in order to retain them in their preferred flat tubular shape heat radiating reinforcing fins 22 are mounted with close sliding friction fit on each section and are spaced sufficiently close to each other to prevent distortion of the sections under any condition of pressure to which they may be subjected. Each fin has a flange 23 extending at right angles thereto and closely fitting the section on which it is mounted, and, these flanges and fins are soldered to the sections in order to provide the greatest possible heat conductive connection between the fins and sections.

In order to permit the assembling of the fins on the sections, the split couplings are so designed that when their inner faces 24 and 25 are moved into contact with each other, the distance between their outer faces 26 and 27 is less than the distance between the parallel faces 6 and 7 of the section plates 2 and 3, it being understood of course, that the bridge plates 16 slide freely on the rod 17, which, obviously must be shorter than the distance between the faces 6 and 7 of the section plates. The bridge members 16 are adapted to receive a suitably formed wrench whenever it becomes necessary to rotate the coupling member connected thereto for the purpose of assembling or disassembling the section of a unit.

I claim:

1. A radiator comprising a plurality of tubular sheet metal sections each of which is provided at each end with aligned apertures, a coupling member slidable and rotatable in each aperture and having an annular shoulder preventing its removal from the section in which it is mounted, and means inside such section for slidably connecting the said members to each other.

2. A radiator section for high pressure systems comprising a pair of plates having their edges welded together and shaped to form a tube closed at each end and having axially aligned apertures in the opposite plates near each end of the section, coupling members mounted to slide and rotate independently in each of said apertures and having shoulders to prevent removal thereof from said apertures, and means connecting said members slidably to each other.

3. A radiator section comprising a flat tube closed at each end and having the sides thereof provided with axially aligned apertures, a shouldered coupling member having a screw-threaded cylindrical part slidable and rotatable in each aperture, and projecting therethrough, and means to retain the said members in said apertures.

4. A radiator section comprising a flat tube

closed at each end and having the sides thereof provided with axially aligned apertures, fins spaced apart lengthwise on said section, and collapsible couplings in each end of said section adapted when extended to prevent removal of the fins from the section and when collapsed to permit the passage of the fins thereover.

5. A radiator section comprising a flat tube having the ends thereof closed and having axially aligned apertures through the opposite flat sides thereof, a coupling in each aperture having an annular shoulder adapted to engage the inside of one of the sides of said tube and a screwthreaded cylindrical projection rotatable and slidably in said aperture, a bridge plate extending diametrically across the shouldered end of said coupling and having an aperture therethrough at the axis of said coupling, and a rod slidable in the apertures of adjacent couplings in the end of a section to prevent complete separation of said couplings and dropping thereof within the section.

6. A coupling for radiating sections comprising a pair of cylindrical screwthreaded members having annular shoulders at one end thereof, and means slidably and rotatably connecting said members to each other to hold them in axial alignment with each other throughout their relative sliding and rotary movements.

7. A coupling comprising a cylindrical rod, a pair of shouldered cylindrical externally screwthreaded members mounted to slide and rotate on said rod, and means at each end of said rod to limit the sliding movements of said members thereon.

8. A coupling comprising a pair of cylindrical externally screwthreaded members each having a centrally apertured bridge plate extending diametrically across said member, a rod mounted to slide and rotate in each of said apertures and a head formed on each end of said rod to limit the sliding movement of one member relative to the other.

In testimony whereof I affix my signature.

AUSTIN H. HART.
